SCREWING AND UNSCREWING TONGS, PARTICULARLY FOR DRILLING PIPE JOINTS

Vladimir Edelberg, Tunis, Tunisia

Application January 31, 1947, Serial No. 725,421
In France June 28, 1946

6 Claims. (Cl. 255—35)

1

The present invention relates to improvements in tongs for making and breaking threaded joints of drilling pipes and drill rods used for drilling holes, particularly for oil wells. The various steps involved in the making and breaking of said threaded joints between the sections or stands of well pipe are of primary importance. For example, in order to change a worn out boring tool at a depth of 9000 feet, more than 220 joints must be made and then broken so that it is essential to reduce to a minimum the time necessary for performing the steps of screwing and unscrewing the threaded joints.

One of the objects of the present invention is to provide a novel self-powered tongs assembly which is permanently supported by the sub-structure of the rotary table of the drilling plant in order to be always ready for operation.

Another object of the invention is to provide self-powered tongs with which the steps of free screwing and of hard tightening can be performed in one single continuous operation without intermediate manoeuvres when making a joint, as well as the steps of breaking and of free unscrewing of the joint.

Still another object of the invention is to provide self-powered tongs of the "internal reaction" type comprising gripping means or sets of jaws adapted to engage the pipe string at both sides of the joint and driving means supported by the tongs assembly and adapted to produce relative rotation of the gripping means in either direction, whereby one of the sets of jaws forms the necessary fulcrum against which the action of the other set of jaws is exerted.

With these and other objects in view, the tongs according to the invention are mainly characterized by the fact that they comprise two cylindrical housings rotatably arranged the one above the other concentrically to the pipe string so as to rotate with respect to one another, an annular member inside of, and rotating with, each of said housings and a crown arranged to rotate freely with respect to each housing, a set of arms pivoted on said annular member and provided at their inner ends with jaws pivoted thereon, control links each pivoted on said crown and on one of the jaw-carrying arms, handles on each crown for tightening both sets of jaws on the pipe at both sides of the joint respectively, guiding means for allowing the vertical displacement of one of the crowns together with the corresponding annular member with respect to their cylindrical housing, power means supported by one of said housings

2

and driving connections for rotation of the second housing by said power means.

The invention will be better understood from the following description in conjunction with the accompanying drawings wherein:

Fig. 1 is a plan view of the tongs assembly.

Fig. 2 shows the tongs in elevation and partly in vertical section.

Fig. 3 is a partial elevational view showing the tongs in the position corresponding to the beginning of the screwing.

Fig. 4 is a perspective view showing the tongs in the position corresponding to the beginning of the unscrewing.

15 The tongs assembly shown in the drawings comprises a base plate 1 (Fig. 2) provided with a central aperture concentrically arranged to the pipe string and which is supported by a plurality of fluid-operated pistons 2, 2' of which the cylinders (not shown) are fixed on the sub-structure of the rotary table of the drilling plant in a manner to enable the tongs to be displaced vertically and to be brought exactly to the height of the joint to be made or broken. A lower cylindrical 20 housing 3 is rotatably supported on said base plate 1 by means of rollers 4. Within the housing 3 is rotatably arranged a crown 5. The base plate 1 is provided with a plurality of spring-pressed balls 6 cooperating with depressions 6' provided on the lower face of crown 5 which allow the latter to be immobilized with respect to plate 1. Within the housing 3 and above crown 5 is an annular member 7 provided with ribs 7' engaging vertical grooves 7'' provided on the inner face of the housing 3. Four arms 9, 9', 9'', 9''' are pivoted on the annular member 7 by means of trunnions 8, 8', 8'', 8''' and the free ends of the arms carry jaws 10, 10', 10'', 10''' pivoted thereon, whereas control links 11, 11', 11'', 11''' are pivoted at one end on crown 5 by means of pivots 12, 12', 12'', 12''' and at the other end on the jaw-carrying arms 9, 9', 9'', 9''', so that a relative rotation between crown 5 and annular member 7 causes the arms 9 to swing inwardly and to bring the jaws 10 in contact with the pipe string below the joint.

An upper housing 14 rotatably supported on the lower housing 3 by means of conical rollers 13 contains an upper annular member 15 provided on its periphery with vertical ribs 16 (Figs. 1 and 2) engaging vertical grooves 17 provided on the inner side of housing 14, the annular member 15 being thus permitted to be displaced vertically without rotating with respect to housing 14. The upper annular member 15 is pro-

vided in the same manner as the lower annular member 7 with four arms 18, 18', 18'', 18''' pivoted on member 15 by means of pivots 19, 19', 19'', 19''' and carrying on their free ends jaws 20, 20', 20'', 20''' pivoted at 21, 21', 21'', 21''''. A crown 22 rotatably arranged in the housing 14 above the annular member 15 is provided with four control links 23, 23', 23'', 23''' pivoted at one end on the crown 22 at 24, 24', 24'', 24''' and at the other end on the jaw-carrying arms 18, 18', 18'', 18''' at 25, 25', 25'', 25''' respectively. The control crown 22 is provided with handles 26 by means of which it can be rotated in order to bring the jaws 20 in contact with the pipe string above the joint. The upper annular member 15 is supported within the housing 14 by spring-pressed cup-shaped members 27 (Fig. 2) and it is further provided with pins 28 traversing vertical slots 29 provided in the upper housing 14 and bearing upon an outer cam ring 30 freely supported by pins 31 screwed in the housing 14. The cam ring 30 is provided with handles 32 and has its upper and lower edges symmetrically sloped so as to form a cam which cooperates with the pins 28 of the annular member 14 to cause said member to be raised or lowered when the ring 30 is rotated by means of handles 32.

The lower housing 3 carries driving means illustrated as three pairs of electrical motors 33-34, 33'-34', 33''-34'', driving worms 35, 35', 35'' respectively meshing with a toothed crown 36 provided at the lower part of the upper housing 14 which is also provided with handles 37.

The operation of the self-powered tongs assembly described above is as follows:

In order to unscrew a threaded joint of the pipe string 38 (Fig. 4) which is assumed to be set on the slips, the upper jaw-carrying arms 18 are brought into the position shown in Fig. 1, i. e. to the right of the radial position with each jaw 20 on the left side of the corresponding arm, whilst the lower jaw-carrying arms 9 are brought in the position shown in dotted lines for one of said arms in Fig. 1, i. e. to the left of the radial position with jaws 18 on the right side of the arm. The cam ring 30 is then rotated by means of the handle 32 in order to bring the annular member 15 in its lowest position within housing 14, as shown in Fig. 4. The operator then raises the tongs by means of the fluid-operated pistons 2, 2' so that the annular member 15 is at the same level as the upper part of the joint to be unscrewed.

The operator now rotates the control crown 22 in a clockwise direction by means of handles 26 until the jaws 20 firmly engage the upper part of the joint. The motors 33, 34 etc. are then started so that the upper housing tends to rotate counterclockwise, tightening the jaws 20 on the joint. No unscrewing takes place, however, because the lower set of arms 9 and jaws 10 are not tightened on the lower part of the joint. The rotation of the motors causes the lower housing 3 to rotate clockwise together with the lower annular member 7 and lower control crown 5 until the spring-pressed balls 6 register with the depression 6' provided on said crown which is thus immobilized, and as the annular member 7 still rotates clockwise with housing 3, the jaws carried by arms 9 are brought in contact with the lower part of the joint and tightened thereon. The rotation of housing 3 is then stopped due to the gripping of jaws 10 on the pipe string. The

torque developed by motors 33, 34 etc. rapidly increases and is transmitted by the two sets of jaws 10 and 20 to the two corresponding pipe sections in opposite directions. At a certain moment the joint is broken, whereupon the upper housing 14 begins to rotate rapidly until the joint is completely unscrewed. The operator immediately stops the motors and, by means of handle 26, rotates the control crown 22 counterclockwise in order to open the jaws 20 carried by arms 18. The operator then starts the motors in the opposite direction while preventing the upper housing 14 from being rotated by holding one of the handles 37, thus imparting by reaction a counter-clockwise rotation to the lower housing 3 which results in the release of arms 9 and jaws 10.

When two sections of pipe are to be screwed together, the position of arms 9 and 18 is inverted with respect to that shown in Fig. 1 and the annular member 15 is brought to its raised position by rotating the sloped ring 30 by means of handles 32, as shown in Figs. 2 and 3, the pins 28 fixed on member 15 and cooperating with said sloped ring 30 sliding upwards within the slots 29 provided in the upper housing 14 during the rotation of the ring 30 thereby causing the raising of member 15. The jaws are set in contact with the pipe and tightened in a manner similar to that described above for unscrewing the joint, with the exception that the housings 3 and 14 are rotated in the opposite direction and the sloped ring 30 is brought to its lowest position shown in Fig. 4 as soon as the jaws 20 are tightened in order to allow the annular member 15 carrying said jaw to move downwardly during the screwing up of the joint.

In the first step the upper part of the joint is rapidly rotated, the friction of the lower housing 3 against the base plate 1 being sufficient to prevent said housing from turning. During the step of hard tightening of the joint, the increase of the torque developed by the motors causes the lower housing to be rotated until the balls 6 of the base plate 1 fall within the depressions 6' of the control crown 5 causing the arms 9 and jaws 10 to be tightened on the pipe and blocking the housing 3. The hard tightening of the joint being thus obtained, the arms 9, 18 and jaws 10, 20 are released in the same way as in the case of the unscrewing described above.

What I claim is:

1. A self-powered tongs assembly for making and breaking threaded joints of drilling pipes and drilling rods, particularly for drilling oil wells, comprising two cylindrical housings rotatably arranged the one above the other concentrically to the pipe string so as to rotate with respect to one another, an annular member inside each of said housings rotating therewith and a crown arranged to rotate freely with respect to each of said housings, a set of arms pivoted on each of said annular members and provided at their inner ends with jaws pivoted thereon to engage separate sections of the pipe respectively, control links each pivoted on said crown and on one of the jaw-carrying arms to swing said arms inwardly upon relative rotation of the crown and annular member, handles fitted on the upper crown for rotating the crowns to tighten both jaw sets on separate sections of the pipe at both sides of the joint respectively, guiding means for allowing the vertical displacement of one of the annular members together

With the corresponding control crown with respect to their cylindrical housing to follow the relative vertical displacement of the separate sections of the pipe when screwing and unscrewing the joint, power means supported by one of said housings and driving connections between the power means and the other housing for effecting relative rotation of the housings to rotate said separate pipe sections relative to one another.

2. A self-powered tongs assembly for making and breaking threaded joints of drilling pipes and drilling rods, particularly for drilling oil wells, comprising a vertically adjustable base plate provided with a central aperture concentric with the pipe string, two cylindrical housings rotatably supported by said plate and arranged one above the other so as to rotate with respect to one another, an annular member disposed concentrically inside each of said housings and rotating therewith, a crown arranged to rotate freely with respect to each of said housings, a set of arms pivoted on said annular member and provided at their inner ends with jaws pivoted thereon to engage separate sections of the pipe at opposite sides of the joint respectively, control links each pivoted on said crown and on one of the jaw-carrying arms to tighten both jaw sets on said separate pipe sections upon relative rotation of the crown and annular member, guiding means for allowing the vertical displacement of one of the annular members together with the corresponding control crown with respect to their cylindrical housing to follow the relative vertical displacement of the respective pipe sections when screwing and unscrewing the joint, power means supported by one of said housings and driving connections for rotation of the second housing by said power means to rotate said separate pipe sections relative to one another.

3. A self-powered tongs assembly for making and breaking threaded joints of drilling pipes and drilling rods, particularly for drilling oil wells, comprising a vertically adjustable base plate provided with a central aperture concentric with the pipe string, fluid pressure means for raising and lowering said base plate, two cylindrical housings rotatably supported by said plate and arranged one above the other so as to rotate with respect to one another, an annular member disposed inside each of said housings and rotating therewith, a crown arranged to rotate freely with respect to each of said housings, a set of arms pivoted at spaced points on said annular member and provided at their inner ends with jaws pivoted thereon to engage two separate pipe sections at opposite sides of the joints respectively, control links each pivoted on said crown and on one of the jaw-carrying arms, means for rotating each crown to tighten both jaw sets on the pipe at both sides of the joint respectively, guiding means for allowing the vertical displacement of one of the annular members together with the corresponding control crown with respect to their cylindrical housing to follow the relative vertical displacements of said pipe sections when screwing and unscrewing the joint, power means supported by one of said housings and driving connections for rotation of the second housing by said power means to rotate said separate pipe sections relative to one another.

4. A self-powered tongs assembly for making and breaking threaded joints of drilling pipes

and drilling rods, particularly for drilling oil wells, comprising a vertically adjustable base plate provided with a central aperture concentric with the pipe string, a first cylindrical housing rotatably supported by said base plate, a rotatable crown within said housing, means for immobilizing said crown with respect to the base plate, an annular member arranged above said crown and arranged to rotate with the housing, a second cylindrical housing rotatably arranged above the first, vertical guides provided on the inner face of said upper housing, an annular member provided with portions engaging the guides of the housing, means for vertically dis-
10 placing said annular member with respect to its housing, a freely rotatable crown arranged in said housing above the said annular member, a set of arms pivoted at spaced points on each of said annular members and provided at their inner ends with jaws pivoted thereon, a set of control links to engage two separate pipe sections at opposite sides of the joint respectively, pivoted on each of the freely rotating crowns and on the corresponding jaw-carrying arms, means for
15 rotating each crown for tightening both jaw sets on the separate sections of the pipe at opposite sides of the joint respectively, power means supported by the lower housing and driving connections for rotation of the upper housing by said power means to rotate said separate pipe sections in opposite directions while the relative vertical displacement of said sections caused by the screwing and unscrewing of the joint is permitted by said vertical guides between the upper
20 housing and annular member.

5. A self-powered tongs assembly for making and breaking threaded joints of drilling pipes and drilling rods, particularly for drilling oil wells, comprising a vertically adjustable base plate provided with a central aperture concentric with the pipe string, a first cylindrical housing rotatably supported by said base plate, a freely rotating crown within said housing, spring-pressed balls provided on the base plate and cooperating with depressions provided in said crown for immobilizing same with respect to the base plate, an annular member arranged above said crown and rotatable with the housing, a second cylindrical housing rotatably arranged above the first, vertical grooves provided on the inner face of said upper housing, an annular member provided with outer vertical ribs engaging the grooves of the housing, vertical slots provided in said upper housing, radial pins
40 fixed to the annular member and projecting out through said slots, an outer ring supported by said upper housing and rotating freely thereon, the edges of said ring being sloped to form a cam
45 cooperating with the pins fixed to the annular member for raising and lowering said annular member within the housing, a freely rotatable crown arranged in said housing above the said annular member, a set of arms pivoted on each of said annular members and provided at their inner ends with jaws pivoted thereon to engage two separate pipe sections at opposite sides of the joint respectively, a set of control links pivoted on each of the freely rotating crowns and on the corresponding jaw-carrying arms, means for
50 rotating each crown for tightening both jaw sets on the said two separate pipe sections, power means supported by the lower housing and driving connections for rotation of the upper housing by said power means to rotate said separate pipe sections in opposite directions, while the
55
60
65
70
75

Resulting vertical displacement thereof caused by the screwing and unscrewing of the joint is permitted by said groove and rib connection provided between the upper housing and the annular member associated therewith.

6. A self-powered tongs assembly for making and breaking threaded joints of drilling pipes and drilling rods, particularly for drilling oil wells, comprising a vertically adjustable base plate provided with a central aperture concentric with the pipe string, a first cylindrical housing rotatably supported by said base plate, a freely rotating crown within said housing, spring-pressed balls provided on the base plate and cooperating with depressions provided in said crown for immobilizing same with respect to the base plate, an annular member arranged above said crown and rotatable with the housing, a second cylindrical housing rotatably arranged above the first, vertical grooves provided on the inner face of said upper housing, an annular member provided with outer vertical ribs engaging the grooves of the housing, vertical slots provided in said upper housing, radial pins fixed to the annular member and projecting out through said slots, an outer ring supported by said upper housing and rotating freely thereon, the edges of said ring being sloped to form a cam cooperating with the pins fixed to the annular member for raising and lowering said annular member within the housing, a freely rotatable crown arranged in said housing above the said annular member, a set of arms pivoted on each of said annular members and provided at their inner ends with jaws pivoted thereon to engage two

separate pipe sections at opposite sides of the joint respectively, a set of control links pivoted on each of the freely rotating crowns and on the corresponding jaw-carrying arms, handles on each crown for tightening both jaw sets on the said separate pipe sections, three groups of two motors having horizontal shafts and supported by the lower housing, three worms driven by the three motor groups respectively, and a toothed crown fixed to the lower part of the upper housing and meshing with said worms whereby a relative rotation of the housings and the respective separate pipe sections is obtained to make and break the joint, while the resulting relative vertical displacement of said pipe sections is permitted by the said groove and rib connection between the upper housing and the associated annular member.
